UNITED STATES PATENT OFFICE.

CHARLES A. HIBSCHMAN, OF SPRINGFIELD, OHIO.

FLUID-DISPENSER.

1,175,060.

Specification of Letters Patent. Patented Mar. 14, 1916.

Application filed July 20, 1914. Serial No. 851,967.

To all whom it may concern:

Be it known that I, CHARLES A. HIBSCHMAN, a citizen of the United States, residing at Springfield, in the county of Clark 5 and State of Ohio, have invented certain new and useful Improvements in Fluid-Dispensers, of which the following is a specification.

My invention relates to fluid dispensing 10 apparatus and particularly to means for agitating the fluid at the time of its withdrawal.

The object of the invention is to simplify 15 the structure as well as the means and mode of operation of such devices whereby they will not only be cheapened in construction, but will be more efficient in use, positive in action, easily operated, and unlikely to get out of repair.

20 With the above primary and other incidental objects in view, as will more fully appear in the specification, the invention consists of the features of construction, the parts and combinations thereof, and the 25 mode of operation, or their equivalents, as hereinafter described and set forth in the claims.

Referring to the drawings, Figure 1 is a 30 longitudinal sectional view of the assembled device in its normal or closed position. Fig. 2 is a similar view of the device in its open position. Fig. 3 is a longitudinal sectional view of a modification of the construction shown in Figs. 1 and 2.

35 Like parts are indicated by similar characters of reference throughout the several views.

The apparatus, forming the subject matter hereof, is especially designed for use in 40 dispensing such commodities as are inclined to separate into portions of different densities when left in a state of rest. It is particularly adapted for use in connection with containers of milk or butter-milk or similar 45 commodities in which the more desirable portions tend to rise to the top, or in dispensing paints and other commodities which contain heavier portions tending to settle toward the bottom.

50 The primary object is to violently agitate the contents of the container prior to the withdrawal of the same in order to insure the discharged portion being of average density.

55 Referring to the drawings, 1 is a portion of a vat or container. Located adjacent to

the bottom thereof is a cylinder 2, the opposite heads of which are perforated as at 3 and 3^a. Extending from the cylinder 2 through the wall of the vat or container is 60 a tubular conduit 4. Any suitable means such as the packing gland 5 and the jam nut 6 with the washer 7 of packing material may be employed to prevent the leakage of the contents of the receptacle around the 65 conduit. Located upon the portion of the conduit projecting beyond the vat or container is a pendant discharge nozzle 8 communicating with the interior of the conduit 4. Within the cylinder 2 is a reciprocatory 70 piston 9, the stem 10 of which extends through the tubular conduit 4 and terminates in a handle 11. A closure cap is provided upon the extremity of the conduit 4 which provides a bearing for the outer portion of the stem 10 which reciprocates therethrough. The interior diameter of the tubular conduit 4 is somewhat greater than the diameter of the stem 10. Substantially mid length upon the stem 10 is a piston like closure body 12, moving therewith, which assumes a position forward of the discharge nozzle 8, as shown in Fig. 2.

In the normal position of the parts, as shown in Fig. 1, the contents of the container are prevented from escaping through the conduit 4 and the discharge nozzle 8 by the closure body 12. When it is desired to discharge a portion of the contents of the container, the piston 9 is drawn forward by 85 means of the handle 11. This causes the contents of the cylinder 2 to be forcibly discharged through the orifices 3^a in the forward head of the cylinder, while at the same time, additional fluid is drawn into the cylinder in the rear of the piston through the orifices 3. The discharge and injection of the fluid from and into the cylinder by the movement of the piston violently agitates the contents of the vessel or container thoroughly mixing any separated portions of unequal density. As the piston 9 and stem 10 continue to move forward, the closure body 12 is drawn to a position beyond the discharge nozzle 8, as shown in Fig. 2. In 90 this position the parts come to rest. The conduit 4 is then open for a discharge of the fluid. The discharged fluid enters the cylinder 2 from the vessel through the orifices 3^a and passes thence through the conduit 4 about the stem 10, escaping through the nozzle 8. To increase the capacity of the 95 100 105 110

apparatus, that portion of the stem 10 intermediate the closure body 12 and the piston head 9 is preferably of reduced diameter. Upon the closing operation, the flow 5 of the contents from the container is arrested upon the initial movement of the piston by the movement of the closure body 12 past the discharge nozzle 8. After the flow of the contents has been arrested, the piston 10 continues to move rearward expelling the contents of the cylinder through the orifices 3 and drawing a new charge thereinto through the orifices 3^a. This again violently agitates the contents of the vessel 15 preparatory to the next withdrawal. It is to be noted that the agitation of the fluid is automatically caused by the opening of the faucet. Such agitation, however, is produced before the faucet is opened sufficiently 20 to permit the flow of the contents. Upon the return movement, the agitation occurs after the faucet has been closed.

In Fig. 3 there is shown a modification of the construction previously described in 25 which the agitator and faucet are independent and separate one from the other. In this construction, the cylinder 2 is provided with a tubular conduit 13, the bore of which is substantially equal to the diameter of the 30 stem 10 of the piston 9. The stem 10 of the piston projects through the tubular conduit 13, as before described, and carries at its extremity the handle 11. The conduit 13 is provided with a packing gland 5 and jam 35 nut 6, as before described. In this construction, however, there is no discharge nozzle 8 leading from the conduit and no closure member 12. Adjacent to the agitator is a faucet 14 of any suitable construction. In using this form of device the handle 11 is withdrawn and returned to reciprocate the piston 9 within the cylinder 2 thereby causing the contents of the cylinder 40 to be forcibly discharged through the orifices 3 and 3^a and new charges drawn thereinto. This violently agitates the contents of the vessel immediately after which the faucet 14 is opened to withdraw the contents in the usual manner. The particular arrangement 45 50 as shown in the drawings, wherein the cylinder 2 is located in a horizontal position adjacent to the bottom of the vessel or container, has been found especially efficient in agitating such commodities as milk or butter-milk and is far superior to any method 55 of agitating such commodities by stirring or by an agitator working from the top or in a vertical position.

From the above description it will be apparent 60 that there is thus provided a device of the character described, possessing the particular features of advantage before enumerated as desirable but which obviously is susceptible of modification in its form, proportion, detail construction or arrangement

of parts, without departing from the principle involved or sacrificing any of its advantages.

Having thus described my invention, I claim:

1. In a fluid dispensing apparatus, a vessel having a discharge orifice, a movable closure for the discharge orifice, a horizontally disposed cylinder located adjacent to the bottom of the vessel, a piston within the cylinder, said cylinder having orifices therein through which a portion of the contents of the vessel are drawn into the cylinder and returned from the cylinder to the vessel by the movement of the piston, and a reciprocatory actuating rod common to both the piston and the movable closure for the discharge orifice, said rod being adapted by its initial reciprocatory movement to actuate the piston to agitate the contents of the vessel and by further reciprocatory movement to move the closure member to permit the discharge of the agitated contents of the vessel. 75 80 85

2. In a fluid dispensing apparatus, a vessel having a discharge outlet, a reciprocatory rod extending through the wall of said vessel, two heads carried in tandem relation by said common rod, one of said heads normally serving to close the discharge outlet, the other head serving to agitate the contents of the vessel, both heads being simultaneously operated by the manual reciprocation of the said rod. 90 95

3. In a fluid dispensing apparatus, a vessel having a discharge outlet, a reciprocatory agitator within the vessel, a closure for said discharge outlet with which the reciprocatory agitator is operatively connected whereby the movement of said outlet closure 100 105 will automatically operate the reciprocatory agitator in unison therewith.

4. In an apparatus of the character described, a vessel having a discharge outlet, a movable closure therefor, a reciprocatory agitator within the vessel, and an actuating rod common to the movable closure and reciprocatory agitator whereby the operation of said closure to open the discharge outlet will simultaneously operate the agitator to 110 115 agitate the contents of the vessel prior to the discharge thereof.

5. The combination with a vessel having an outlet orifice of a horizontally disposed cylinder having inlet and outlet orifices submerged in the contents thereof, a reciprocatory piston within the cylinder, a closure for the outlet orifice and means to reciprocate the piston in unison with the movement of the outlet orifice closure. 120 125

6. In a fluid dispensing apparatus, a vessel, a discharge conduit leading therefrom, a reciprocatory valve in said conduit and an agitator within the vessel actuated by the movement of the valve. 130

7. In a fluid dispensing apparatus, a vessel, a conduit leading therefrom having a laterally disposed discharge orifice, a reciprocatory plunger valve in said conduit mov-

5 able alternately to positions on opposite sides of the discharge orifice, and an agitator within the vessel operated by the move-

ment of the valve.

8. In a fluid dispensing apparatus, a ves-
10 sel having a discharge outlet, a reciprocatory rod extending horizontally through the wall of the vessel, an agitating head carried by said rod within the vessel, and a closure member also carried by the rod adapted by
15 the movement of the rod to open and close the discharge outlet of the vessel.

9. In a fluid dispensing apparatus, a ves-
10 sel, a cylinder having inlet and outlet ori-
fices submerged in the contents of the vessel,
20 a discharge conduit leading from the cylin-
der through the side wall of the vessel, a
piston within the cylinder, a piston rod ex-
tending through said conduit, and a closure
25 member for the discharge conduit carried by
the piston rod.

10. In a fluid dispensing apparatus, a ves-
sel, a horizontally disposed cylinder having
inlet and outlet orifices submerged in the
contents of the vessel, a conduit leading
30 therefrom through the wall of the vessel and
having a laterally disposed discharge orifice
therein, a piston rod extending through the
conduit, a piston head within the cylinder

carried by said rod and a second piston head
within the conduit carried by the rod, the
35 path of travel of the second piston head be-
ing across the lateral discharge orifice of
the conduit.

11. A fluid dispensing apparatus comprising
ing a container for the fluid, a faucet, an 40
agitator within the container, and an op-
erating member for the agitator extending
substantially horizontally through the side
wall of the container by which the agitator
may be actuated to disturb the contents of 45
the container prior to their withdrawal
through the faucet.

12. In an apparatus of the character de-
scribed, a vessel, an outlet conduit therefor,
a cylinder within the vessel, a reciprocatory 50
piston rod, two piston heads carried by said
rod, one of said heads being located to re-
ciprocate within said outlet conduit and nor-
mally serving to close said conduit, the other
piston head being mounted to reciprocate 55
within the cylinder and serving to agitate
the contents of the vessel, both piston heads
being simultaneously operated by the opera-
tion of said rod.

In testimony whereof, I have hereunto set 60
my hand this 16th day of July.

CHARLES A. HIBSCHMAN.
